Patented June 11, 1912.

UNITED STATES PATENT OFFICE.

EVERETT R. BURTNETT, OF SAN MATEO, CALIFORNIA, ASSIGNOR OF ONE-THIRD TO
ROBERT E. BOWIE AND ONE-THIRD TO THOMAS O. HEYDENFYLDT, BOTH OF RED-
WOOD CITY, CALIFORNIA.

INTERNAL-COMBUSTION ENGINE.

1,029,419.

Specification of Letters Patent. Patented June 11, 1912.

Application filed May 15, 1911. Serial No. 627,195.

To all whom it may concern:

Be it known that I, EVERETT R. BURTNETT, a citizen of the United States, residing at San Mateo, in the county of San Mateo and State of California, have invented new and useful Improvements in Internal-Combustion Engines, of which the following is a specification.

The object of the present invention is to provide an internal combustion engine of very simple construction, efficient in operation, and not liable to get out of order.

In the accompanying drawing, Figure 1 is a vertical section, partly in side elevation, taken on the line 1—1 of Fig. 2; Fig. 2 is a similar view taken on the line 2—2 of Fig. 1; Fig. 3 is a detail horizontal section immediately above the upper end of the pitman of the engine.

20 The crank shaft 1 of the engine, carrying the fly wheel 2 is journaled in upper and lower boxes 3, 4, of which the lower boxes 4 are screwed to the upper boxes 3, while the upper boxes are formed integral with 25 cross pieces 5 which extend between, and are integral with, standards 6 formed on a base plate 7. Said standards are formed at the top with a circular flange 8, to which is bolted, as shown at 9, a circular flange 10 of an upwardly extending cylindrical intake and compression casing 11, having a water jacket 12, supplied with water by a conduit having a water inlet 13 and a water outlet 14. Said casing is closed at the top 30 except for a valve seat 15, against which is pressed upwardly a gas inlet valve 19, said seat 15 communicating with a pipe leading to a carburetor.

In the intake and compression chamber 40 reciprocates vertically a piston 20 having packing rings 21, and formed integral with a cylinder 22, the lower edge of which is formed with diametrically opposite pairs of depending lugs 23 connected by an apertured cross head 24 carrying at the center a pin 25. Through the aperture in said cross head is passed, and secured by the pin 25, the end of a pitman 26. Said pitman is secured by a half-box 30 to the 50 crank 29 of the crank shaft 1.

The object of operatively connecting the lower end of the cylinder 22 with the crank shaft by means of the crosshead is to enable the cylinder 22 to reciprocate outside

of, and in close contact with, a stationary 55 cylindrical abutment 33, while said abutment is stationarily supported by supports 36, secured to the cross pieces 5 by screws 28. These supports 36 for the abutment 33 are located laterally, or at a distance from 60 the center of the abutment, thereby permitting the cross-head 24 to extend centrally with reference to the cylinder or extension 22. Said abutment supports a spark plug 40, and in order to permit it to so support 65 said spark plug, while so permitting the cylinder to freely reciprocate past said supports 36, said supports are arranged as shown in Fig. 3, one of them to one side of a diametral line through the center of 70 the other. The supports 36 for the abutment 33 are made vertical in their upper portions to permit of vertical reciprocation of the cylinder 22 and are extended obliquely in the lower portions to permit of 75 the revolution of the crank.

16 is an exhaust port in the wall of the cylinder 22, which is adapted to register with an exhaust port 17 in the cylinder 11.

18 is a transfer valve to permit the 80 compressed gases to pass from the compression chamber to the combustion chamber.

The operation of the engine is as follows. Assuming the parts to be in the position shown in Fig. 2, in which the piston is at 85 the lowest part of its stroke the compressed gases in the combustion chamber are ignited by the spark, and combustion takes place, forcing the piston upward. Then the gases, which have been previously drawn into the 90 intake or compression chamber are compressed in said chamber. When the piston has passed through three-fourths of the upward stroke, the pressure of the compressed gases is sufficient to open the transfer valve 95 18. The exhaust valve begins to open when the piston is about three-fourths up, and this being open to the atmosphere the pressure on the lower side of the piston is greatly reduced thus allowing the combustible gases to flow into said combustion chamber, so that said gases pass from said compression chamber into the combustion chamber, and in doing so they drive before them the products of the previous combustion, which pass out through the exhaust port 16 in the cylinder 22 and then through 100 the exhaust port 17 in the casing 11. A

particular advantage arises from locating the transfer valve 18 in the piston 20 itself, rather than in the extension 22 therefrom, because by the above arrangement it results that the combustible mixture, transferred from the compression chamber to the combustion chamber, on entering the latter chamber flows in a direction most effective for the expulsion of the waste gases at the ports 16 and 17. The imperfection of the means for expelling the waste gases has heretofore been one of the principal objections to two-cycle engines. By locating the transfer valve in the piston, the result is obtained that, upon the transfer of the gases from the compression chamber to the combustion chamber, the gases, on passing said valve, completely fill the whole of the upper portion of the combustion chamber, even to the walls thereof, and thus expel substantially all of the waste gases. As the piston continues upward to the top of the cylinder, the transfer valve is still open, and the compressed gases equally fill both chambers. This result, namely, that the transference of combustible gases takes place during the whole of the upward movement of the piston, after said upward movement has been continued sufficiently to compress the gases to open the valve 18, results likewise from the fact that the transfer valve is located in the piston itself. Soon after the down stroke commences in the cylinder, the exhaust port 16 passes the packing rings 33, so that the combustion cylinder is closed, and the transfer valve is also then closed, and further compression then takes place in the combustion chamber. At the same time suction is created in the intake chamber, causing the valve 15 to open and a mixture of combustible gases to flow into said chamber.

The following are the advantages of my improved engine. On account of the upper chamber being of considerably greater diameter and area than the lower or combustion chamber, the gases are compressed in said combustion chamber to a high degree. The engine is entirely free from cams and gears. By drawing the combustible gases direct from the carburetor into the intake chamber, instead of using the crank casing for the compression chamber, said gases do not come in contact with lubricating oil, and the lubrication is in no degree affected by said gases. There is less liability of the engine being damaged by an explosion, as, for instance, by a cylinder head blowing out, since the force of the explosion takes place between the piston 20 and the stationary abutment 33 in the form of a piston.

I claim:—

1. In an internal combustion engine, the combination of a cylindrical casing, a piston fitting closely within and reciprocating in

said casing, a cylindrical extension from said piston, a stationary abutment within said extension provided with suitable laterally located supports, a cross-head centrally connected to said extension at the side of said abutment remote from said piston, a shaft, a crank thereon, a pitman connected to said crank and cross head, means for admitting combustible mixture to the space between said piston and casing, a valve permitting said mixture to pass from said space to the space between the piston and the abutment, and means within said latter space for igniting said combustible mixture, said extension having an exhaust port for the products of combustion.

2. In an internal combustion engine, the combination of a cylindrical casing, a piston fitting closely within and reciprocating in said casing, a cylindrical extension from said piston, a stationary abutment within said extension provided with suitable laterally located supports, a cross-head centrally connected to said extension at the side of said abutment remote from said piston, a shaft, a crank thereon, a pitman connected to said crank and cross head, means for admitting combustible mixture to the space between said piston and casing, a valve in said piston permitting said mixture to pass from said space to the space between the piston and the abutment, and means within said latter space for igniting said combustible mixture, said extension having an exhaust port for the products of combustion.

3. In an internal combustion engine, the combination of a cylindrical casing, a piston fitting closely within and reciprocating therein, a cylindrical extension, a stationary abutment within said extension provided with suitable laterally located supports, a cross-head centrally connected to said extension at the side of said abutment remote from said piston, a shaft, a crank thereon, a pitman connected to said crank and cross-head, means for admitting combustible mixture to the space between said piston and casing, a valve in said piston permitting said mixture to pass from said space to the space between the piston and the abutment, and means within said latter space for igniting said combustible mixture, said extension having an exhaust port for the products of combustion, and said casing having a second exhaust port always open to the atmosphere with which the first-named port is adapted to register in the movement of the piston.

4. In an internal combustion engine, the combination of a cylindrical casing, an exterior casing forming with the first-named casing a water jacket, a piston fitting closely within and reciprocating in said cylindrical casing and having an opening therethrough, said piston having an extension, an abutment forming with said extension and piston

a chamber, the cylindrical casing having in its end an inlet opening into the space between said end and the piston, valves for controlling both of said openings, said piston being provided with an extension, a cylindrical abutment around which said extension reciprocates, laterally located supports for said abutment, a shaft, a crank on said shaft, a pitman connected thereto, a connection between the pitman and the ex-

tension passing between said supports, and a spark plug supported by said abutment, said extension having an exhaust port.

In testimony whereof I have hereunto set my hand in the presence of two subscribing 15 witnesses.

EVERETT R. BURTNELL.
